UNITED STATES PATENT OFFICE.

HARRISON RUSSELL LELAND AND WILLIAM SCHWEMLEIN, OF PARKERSBURG, WEST VIRGINIA, ASSIGNORS TO PARKERSBURG RIG & REEL COMPANY, OF PARKERSBURG, WEST VIRGINIA, A CORPORATION OF WEST VIRGINIA.

DECK FOR OIL TANKS.

1,426,997

Specification of Letters Patent. Patented Aug. 22, 1922.

Application filed May 9, 1921. Serial No. 468,058.

To all whom it may concern:

Be it known that we, HARRISON R. LELAND and WILLIAM SCHWEMLEIN, citizens of the United States, residing at Parkersburg, in the county of Wood and State of West Virginia, have invented certain new and useful Improvements in Decks for Oil Tanks, of which the following is a specification.

This invention relates to decks for oil tanks, and it comprises a floating deck adapted to be arranged on top of the body of oil within the tank, an upwardly extending rim secured thereto, a plurality of collapsible members secured to said rim and engaging the wall of the deck, and yielding means to retain said members in engagement with said wall, said members being capable of being moved inwardly to avoid obstructions in the wall of the tank.

When oil is stored in tanks, a certain amount of evaporation takes place and a large quantity of oil is lost because of this evaporation. The previous construction of oil tanks, wherein the decks were not made gas tight, permits practically free circulation of air through the top of the tank over the body of confined oil which increases the loss due to evaporation. In providing a gas tight deck for an oil tank, it is necessary to provide some means for escape of vapors. While an open top which will permit free escape of vapors and constant circulation of air is undesirable due to the increased evaporation caused, from the standpoint of safety, it is necessary to permit the vapors to escape when the pressure exceeds a safe limit.

In the present invention, we have provided a deck adapted to float on top of a body of oil arranged in a tank, whereby the air space above a partially filled tank is eliminated and evaporation reduced to a minimum. The provision of a floating deck also reduces fire hazard as it eliminates the possibility of the formation of a body of confined vapors at high pressure in the upper part of the tank. The body portion of the rim is of slightly less diameter than the diameter of the tank and a plurality of wall engaging members are secured thereto. The wall engaging members are normally maintained in engagement with the wall by means of springs or other yielding connections. This permits them to adjust themselves to the uneven surface of the conven-

tional oil storage tank, permitting them to move away from the tank when passing overlapping joints in the plates forming the tank structure, rivet heads, or other projections.

In the accompanying drawings, we have shown one embodiment of the invention. In this showing:

Figure 1 is a side elevation of a tank with the deck in position, parts being shown in section,

Figure 2 is an enlarged vertical sectional view of a portion of a tank and deck,

Figure 3 is a plan view,

Figure 4 is a detail perspective view, and,

Figure 5 is a view similar to Figure 2 showing a slightly different construction.

Referring to the drawings, the reference numeral 1 designates generally, an oil tank provided with a suitable inlet 2 and outlet 3. As shown, the tank may be formed in sections, an upper section 4 being secured to the tank, as at 5. A body of oil 6 is represented within the tank.

The floating deck comprises a base, or body portion 7 of slightly less diameter than the diameter of the tank, and an upwardly extending rim 8 is secured to the base. As shown, the rim is provided with a lower flange 9 for the reception of suitable fastening means 10, passing through the base and is further provided with an upper flange 11.

The wall engaging members consist of a plurality of plates 12, a portion of which are arranged in a substantially vertical plane 90 and extend from the base of the deck to the wall of the tank 1. Each of the plates is extended at an angle, as at 13, in a substantially horizontal plane and rests upon the upper flange 11 of the rim. These plates are hinged, as at 14, to suitable supporting members or brackets 15, carried by the base of the deck. A coil spring 16 is arranged between the rim and the plate 12, the coil spring being provided with an arm 17, extending upwardly and engaging the plate, as at 18, the other arm of the spring engaging the rim, as at 19. Adjacent the engagement of the horizontal portion 13 of the hinged plate and the flange 11, a ring of wire gauze 20 may be positioned. This ring is held in position by means of a band 21, secured to the rim of the deck, a portion of the gauze ring being arranged between the rim and the band, as at 22. As shown, a

lining 23 of fabric of similar material may be arranged on the exterior of the rim and extend over the lower flange 9. This lining then extends partially up the plates 12 to prevent passage of the oil vapors and gases through the space between the rim and the plates. The circulation may be further retarded by partially filling the space between the rim and the plates 12 with gravel or other granular material as indicated at 10 24, forcing the gases and the vapors to flow in an irregular path in escaping from the tank.

In operation, the floating deck rises and falls in the tank with the body of oil, being maintained on top of the oil. The movable deck eliminates a gas chamber above the oil when the deck is only partially filled, thus cutting down the circulation 15 of air over the body of oil and material reducing evaporation. The floating deck further eliminates the confinement of a body 20 of gas and vapors within the tank, thereby decreasing possibilities of explosion. The vapors and gases escaping from the body of oil, travel through the spaces between the plates 12, through the fabric lining 23, and the gravel 24 and escape from the tank. This circulation is retarded by the fabric 25 and gravel whereby evaporation is reduced to a minimum but the gases and vapors are carried off at a sufficient rate to prevent accumulation of a body of explosive gases and vapors at a high pressure. As the tank 30 is filled, or emptied, the plates 12 are maintained in engagement with the wall of the tank by means of the springs 16. The springs exert sufficient pressure to normally maintain the plates in engagement with the 35 walls of the tank, but permit the plates to move inwardly when the surface of the tank is uneven, due to overlapping joints, rivet heads, or other obstructions.

In the form of the invention shown in 40 Figure 5 of the drawings, the operation is essentially the same. The section 13 of the plate, however, is eliminated, as it is not always essential that the plate rest upon the flange 11.

It is to be understood that the forms 45 of the invention herewith shown and described are to be taken as preferred examples of the same, and that various changes in the shape, size, and arrangement 50 of parts may be resorted to without depart-

ing from the spirit of the invention or the scope of the subjoined claims.

Having thus described our invention, we claim:

1. The combination with an oil tank, of 60 a floating deck comprising a body portion, smaller in diameter than the diameter of the tank, a rim secured to said body portion and projecting upwardly therefrom, a plurality of overlapping members hinged 65 to the body portion and adapted to contact with the wall of the tank, and means for retaining said members in position.

2. The combination with an oil tank, of 70 a floating deck comprising a body portion of less diameter than the diameter of the tank, an upwardly extending rim secured thereto, a plurality of overlapping hinged members secured to the body portion and arranged circumferentially thereof, and a 75 coil spring secured to each of said hinged members and to the deck to normally maintain said members in engagement with the wall of the tank.

3. The combination with an oil tank, of 80 a floating deck comprising a body portion, the diameter of which is less than the diameter of the tank, an upwardly extending rim secured thereto, a plurality of overlapping plates hinged to said body portion 85 extending upwardly at an angle to contact with the wall of the tank and thence extending inwardly over said rim, and means for normally maintaining said hinged plates in contact with the wall of the tank. 90

4. The combination with an oil tank, of 95 a floating deck comprising a body portion of less diameter than the diameter of the tank, an upwardly extending rim secured thereto, a plurality of overlapping plates hinged to the body portion of the deck and extending upwardly at an angle to contact with the wall of the tank, said plates being provided with extensions engaging the upper end of said rim, and a coil spring secured to each of said plates to normally maintain it in contact with the wall of the tank. 100

In testimony whereof we affix our signatures in presence of two witnesses 105
